DESIGN FOR A LAMP BULB

Clarence Birdseye, Gloucester, Mass., assignor, by
mesne assignments, to Birdseye Electric Corpora-
tion, Dover, Del., a corporation of Delaware

Application June 30, 1936, Serial No. 63,582

Term of patent 14 years

To all whom it may concern:

Be it known that I, Clarence Birdseye, a citizen of the United States, residing at Eastern Point Boulevard, Gloucester, in the county of Essex and State of Massachusetts, have invented a new, original, and ornamental Design for a Lamp Bulb, of which the following is a specification, reference being had to the accompanying drawing, forming a part thereof in which,

Fig. 1 is an end view of a lamp bulb showing my new design,

Fig. 2 is a view of the bulb in side elevation.

The dominant feature of my design resides in the spiral element shown on the end of the bulb in solid black lines, the remainder of the bulb being shown conventionally in dotted lines.

I claim:

The ornamental design for a lamp bulb substantially as shown and described.

CLARENCE BIRDSEYE.
